UNITED STATES PATENT OFFICE.

AXEL A. STROM, OF AUSTIN, ILLINOIS, ASSIGNOR TO STROM MANUFACTURING COMPANY, OF CHICAGO, ILLINOIS.

DESIGN FOR A SWITCH-STAND STANDARD.

SPECIFICATION forming part of Design No. 34,489, dated May 7, 1901.

Application filed April 1, 1901. Serial No. 53,963. Term of patent 14 years.

To all whom it may concern:

Be it known that I, AXEL A. STROM, a citizen of the United States, residing at Austin, in the county of Cook and State of Illinois, have invented and produced a new and original Design for a Switch-Stand Standard, of which the following is a specification, reference being had to the accompanying drawing, forming a part hereof.

My design of switch-stand standard is shown in the drawing by a perspective view.

As shown in the drawing, the leading or material feature of my design consists in the post A, rising from a base B, arched across its under side and terminating at its outer ends in the angular sections a a. The post is surmounted by a substantially sector-shaped ta-

ble C, from the upper side of which, at its opposite ends, project lugs b b, and recesses d d are shown formed in the curved-edge portion 20 of the table in radial lines with the spindle-opening c.

Having described my invention, what I claim as new, and desire to secure by Letters Patent, is—

The design for a switch-stand standard, as herein shown and described.

In testimony whereof I have hereunto signed my name to this specification in the presence of two subscribing witnesses.

AXEL A. STROM.
